UNITED STATES PATENT OFFICE.

JOHN T. BATES, OF PITTSBURGH, PENNSYLVANIA.

FURNACE-BOTTING APPARATUS.

1,154,281.

Specification of Letters Patent. Patented Sept. 21, 1915.

Application filed August 19, 1914. Serial No. 857,511.

To all whom it may concern:

Be it known that I, JOHN T. BATES, a citizen of the United States, residing at Pittsburgh, in the county of Allegheny and 5 State of Pennsylvania, have invented certain new and useful Improvements in Furnace-Botting Apparatus, of which the following is a specification.

My invention relates to the construction 10 of apparatus by which the cinder notch or cinder tapping hole of blast furnaces is plugged or closed and the invention more particularly relates to the construction of the botting bar and bar operating mechanism used in actuating such botting apparatus.

One object of my invention is to provide 20 a furnace botting apparatus having improved means whereby the botting bar is secured and maintained in operative position.

Another object of the invention is to provide a botting apparatus having novel means whereby the botting bar is suspended in 25 front of the cinder notch of the blast furnace and is moved into and out of notch, closing position by an operator at a safe distance away from in front of the cinder notch.

30 Further objects of my invention will be made apparent as the apparatus becomes more fully described hereinafter.

Referring to the drawings, forming part 35 of this specification, Figure 1 is a vertical sectional elevation through the cinder notch or cinder tapping hole of a blast furnace showing a furnace botting apparatus constructed and arranged and applied thereto in accordance with my invention. Fig. 2 is 40 a transverse sectional elevation of the same, the section being taken on the line II—II of Fig. 1. Fig. 3 is a similar transverse section, on the line III—III of Fig. 1. Fig. 4 is a detail plan showing the construction of 45 the swinging outer end of the botting bars forming part of the apparatus shown in Fig. 1. Fig. 5 is a longitudinal section showing a modified form of botting bar as made in accordance with my invention.

50 In the accompanying drawings the numeral 2 designates the cinder notch or cinder tapping hole of a blast furnace 3. The tapping hole is provided with a cooler 4, monkey cooler 5 and cinder monkey 6 which, as 55 shown, are of the usual known construction.

Above the tapping hole 2 and in vertical alinement therewith is a horizontally extending beam or girder forming a support 7 having one end thereof secured to the furnace 3 and the other end fastened to the 60 conveniently located furnace bustle pipe 8. Pivoted at one end to the support 7 by a pivot pin 9 is a depending lever 10 made in sections. The lower section 10^a thereof has its lower end pivotally connected by a pin 65 11 to an intermediate point in the length of the swinging botting arm 12. A second lever 13 having a bent upper end 14 and having a rectangular slot 15 therein adjacent to the bent end 14 also is pivotally attached by 70 a bolt or pivot pin 16 to the support 7, and this lever 13 also is made in sections, the lower section 13^a being pivotally connected by a pin 17 to an intermediate point in the 75 length of the arm 12. The slot 15 in the upper end of the lever 13 is provided with a pivot pin 19 which extends through the slot and is fixed on the support 7. The support 7 has a curved slot 36 therein, through 80 which the pivot pin 16 extends, this pin being fastened to the outer end of the bent end 14 of the lever 13.

The botting arm 12 has a botting bar 20 pivotally secured thereto, the bar 20 being pivoted at one end by a pin or bolt 21 to the 85 arm, by a taper pin 22 removably secured in holes in the ears 23 forming a keeper which is provided adjacent to the end of the arm 12 for that purpose.

The over-lapping ends of the lever sections 10 and 10^a and the lever sections 13 and 13^a have slots 24, 24 therein, through 90 which bolts 25 extend to fasten the lever sections together in adjusted position and to enable the length of these levers to be varied to adjust the botting arm 12 and bring the botting bar into alinement with the cinder notch 2.

Instead of using a solid botting bar 20 like that shown in Figs. 1 and 4, the hollow 100 water cooled botting bar 26 shown in Fig. 5 may be employed. In this construction, the botting end of the botting bar 26 is fastened to the screw threaded end of a hollow member 27, the member 27 having a threaded 105 coupling 28 on its outer end by which a wrought metal nose 29 is removably fastened thereon. A pipe 30 extends within the tubular member 27 to a point adjacent to the end of the tapered nose 29. The inlet 110

opening 31 affords means for supplying water or other cooling fluid through the pipe 30 to the nose 29 of this botting bar and an outlet opening 32 affords means for conducting the cooling fluid from the hollow water cooled botting bar 26.

The apparatus is arranged to swing by gravity into the position relative to the cinder notch as shown in the drawings and 10 guide bars 33 and 34 are provided on the support 7 to prevent transverse swinging of the arm 12.

A rope, or other flexible connection 35 is attached to the lower section 10^a of the swinging lever 10 to provide means for moving the arm 12 and botting bar 20 or when used, the botting bar 26 from the position shown in full lines into that shown in dotted lines or from the cinder notch closing position into position out of the way of and from in front of the cinder notch by an operator stationed at a remotely located point.

The inlet opening 30 and outlet opening 31 on the tubular member 27 of the botting bar 26 is connected by a flexible hose or walking pipe (not shown) to a remotely located point of discharge, when the water cooled botting bar 26 is employed. In the operation of my improved apparatus the botting arm 12 is suspended from the support in the manner shown.

A botting bar 20 having a solid end such as is shown in Figs. 1 and 2 or a water cooled botting bar 26 like that shown in Fig. 5 is pivoted by the bolt 21 to the botting arm 12. Meanwhile the botting arm and botting bar will be held in its retracted position (shown by dotted lines in Fig. 1) by means of the flexible connection 35.

40 When it is desired to open the furnace cinder notch 2, to tap off the cinder or "flush the furnace," the botting bar 20 is pulled backwardly by grasping the botting arm 12 or by pulling upon the connection 35 to move the bar 20 away from the furnace, a winch or winding drum (not shown) which is attached to the flexible connection usually being employed for this purpose.

When the botting bar 20 is moved backwardly into its retracted position, the lever 10 swings backwardly in the arc of a circle, with the pin 9 by which it is pivoted to the support 7 as a center. The other lever 13 moves upwardly on the pin 19 in the slot 15 in the upper end thereof for a portion of the length of the slot and then the pivot pin 16 on the outer end of the bent end 14 of the lever 13 moves downwardly and traverses the curved slot 36 in the support 7 upon further backward swinging movement of the botting arm and botting bar. In this way the rear end of the botting arm 12 is caused to rise vertically while the botting end of the botting bar 20 or 26 moves in a substantially horizontal plane.

When it is desired to close the tapping hole 2, the flexible connection 35 is released and the weight of the suspended portions of the apparatus moves the botting bar 20 from the position shown in dotted lines until the botting bar is substantially horizontal and then moves the bar forward in a general horizontal direction until the botting end of the bar 20 is again inserted in the cinder monkey 6 within the cinder tapping hole. 70 The botting bar 20 then remains in this position until it is again desired to tap cinder from the furnace when the above described operations are again repeated. When desired, the pin 22 in the keeper 23 on the end 75 of the botting arm 12 is removed and the botting bar 20 is swung on the pivot 21 to move it laterally out of the way of, or from in front of the cinder tapping hole 2.

The operation of the apparatus will be 85 the same as has been described when the water cooled botting bar 26 is employed. In such case however flexible connections to the inlet 31 and outlet 32 will be provided in order to conduct cooling fluid to the 90 hollow botting bar and to carry off the waste fluid therefrom.

The advantages of my invention will be apparent to those skilled in the art. By the use of my improved apparatus the 95 operation of tapping or opening and stopping or closing the cinder notch of blast furnaces is easily and quickly performed.

Instead of opening the tapping hole by means of a manually actuated bar, the apparatus is operated from a remote point, away from in front of the tapping hole, and out of the way of flying particles of hot cinder. The apparatus is simple and is easily kept in repair.

Modifications in the construction and arrangement of the parts may be made without departing from my invention as defined in the claims.

I claim:

1. A furnace botting apparatus comprising a swinging botting arm, depending levers to which said botting arm is pivoted, a support for said levers, and means connecting said levers and lever support whereby the rear end of the botting arm is lifted in the backward swinging movement of the arm while the botting end thereof is moved in a substantially horizontal plane.

2. A furnace botting apparatus comprising a swinging botting arm, depending levers to which said botting arm is pivoted, a support for said levers, means connecting said levers and lever support whereby the rear end of the botting arm is lifted in the backward swinging movement of the arm while the botting end thereof is moved in a substantially horizontal plane, and means for actuating said botting arm.

3. A furnace botting apparatus comprising

a hollow botting bar, a swinging arm to which said bar is pivotally fastened, means on said arm for holding the bar in lengthwise alignment with the arm, depending levers to 5 which said arm is pivotally secured, and flexible means leading to the rear end of said botting bar to maintain circulation of a cooling medium within the hollow botting bar while the botting bar is moving into and out 10 of botting position.

4. A furnace botting apparatus comprising a botting bar, a swinging arm to which said bar is pivotally fastened, means on said arm for holding the bar in lengthwise alignment with the arm and depending levers to 15 which said arm is pivotally secured.

5. A furnace botting apparatus comprising a botting bar, a swinging arm to which said bar is pivotally fastened, means on said arm for holding the bar in lengthwise alignment with the arm, depending levers to 20 which the swinging arm is pivoted, a support for said levers and means on said support coating with the levers, whereby the 25 swinging arm is lifted in its backward swinging movement while the botting end of said bar is moved in a substantially horizontal plane.

6. A furnace botting apparatus comprising 30 a swinging botting arm, depending levers to which said botting arm is pivoted, a support for said levers, and a pin and slot connection between at least one depending lever and the lever support connecting said

levers and lever support whereby the rear 35 end of the botting arm is lifted in the backward swinging movement of the arm while the botting end thereof is moved in a substantially horizontal plane.

7. A furnace botting apparatus comprising 40 a swinging botting arm, depending levers to which said botting arm is pivoted, a support for said levers, and means connecting said levers and lever support whereby the rear end of the botting arm is lifted in 45 its backward swinging movement while the botting end thereof is moved in a substantially horizontal plane, and a guide to prevent 50 sidewise swinging of the depending levers.

8. A furnace botting apparatus comprising a swinging botting arm, depending levers to which said botting arm is pivoted, a support for said levers, and means connecting said levers and lever support whereby 55 the rear end of said botting arm is lifted in its backward swinging movement while the botting end thereof is moved in a substantially horizontal plane, and means on the lever support forming a guide to prevent 60 sidewise swinging of the depending levers.

In testimony whereof, I have hereunto set my hand.

JOHN T. BATES.
